UNITED STATES PATENT OFFICE.

WILLARD L. DORR, OF ROCKFORD, ILLINOIS, ASSIGNOR TO BARBER-COLMAN COMPANY,
OF ROCKFORD, ILLINOIS, A CORPORATION OF ILLINOIS.

WARP-FRAME.

938,130.

Specification of Letters Patent. Patented Oct. 26, 1909.

Application filed February 7, 1908. Serial No. 414,819.

To all whom it may concern:

Be it known that I, WILLARD L. DORR, a citizen of the United States, residing at Rockford, in the county of Winnebago and 5 State of Illinois, have invented certain new and useful Improvements in Warp-Frames, of which the following is a specification.

This invention relates to a stretching means and particularly to stretching fibrous 10 material, as, for example, warp threads.

One of the objects of the invention is to provide means for shifting a clamp or other means for holding fibrous material.

Another object is to provide means for 15 stretching warp threads longitudinally of the individual threads.

Another object is to provide means at a 20 plurality of points throughout the length of the clamp to give a shifting movement thereto.

Other objects and advantages as well as the novel details of construction of the invention will be specifically described herein-after, it being understood that changes in 25 form, proportion, and minor details of construction may be resorted to without departing from the spirit of the invention or sacrificing any of the advantages thereof.

In the accompanying drawings, Figure 1 is 30 a side elevational view of a warp supporting frame to which my invention is applied. Fig. 2 is an end view of the same; and Fig. 3 is an enlarged detailed perspective view 35 of a portion of the shiftable clamp and mechanism for imparting movement thereto.

The warp supporting frame may comprise a plurality of yokes 1 connected by the longitudinally extending rods 2. At one side of the frame and carried by the 40 respective yokes is a thread clamp, shown as comprising a channel iron 3 adapted to receive an insertion bar 4. Either the interior of the channel iron, the exterior of the insertion bar, or both, may be provided with 45 facings of rubber or other resilient material to insure clamping contact with the portion of the thread to be clamped and the clamping will be accomplished by means of a bar 5 having a plurality of projections 6 on the 50 faces of which may ride the projections 7 of the longitudinally shiftable bar 8; whereby the insertion bar 4 will be held against removal and will efficiently hold the threads. The rollers 9 are for the purpose of sup-

porting the warp frame on the bed of a 55 machine so that the frame will be conveniently fed longitudinally through the medium of a suitable pinion in mesh with the rack 10.

On the side of the frame opposite to the 60 clamp just described is a shiftable clamp herein shown as comprising a channel iron 11 having an insertion bar 12, and clamping bars 13 and 14 corresponding to the bars 5 and 8 on the opposite side of the frame. 65 The shiftable clamp is provided with a plurality of outstanding projections 15 movable in slots 16 in the yokes 1. The projections 15 are provided at their bases with interlocking members 17 capable of interlocking with the ends of the yokes 1. The interlocking members 17 may comprise dove-tails, and, of course, the ends of the yokes 1 70 will be correspondingly formed to receive the dove-tails to make the sliding connections. 75

The outstanding projections 15 are shown as grooved as at 18 to receive the shifting members 19 illustrated as comprising eccentrics on the longitudinally extending shaft 80 20. The shaft 20 may be oscillated by a lever or handle 21, thus the eccentrics will be moved to shift the shiftable clamp either toward or away from the immovable clamp on the other side of the frame. When the material to be stretched is first placed on the frame, the movable clamp will be shifted toward the immovable clamp and caused to assume a position similar to that shown in Fig. 2. After the material (for example a warp) 90 is placed in the clamps, the shaft 20 may be oscillated by the lever 21 so as to shift the shiftable clamp away from the immovable clamp, so as to stretch the threads or other material. The eccentrics are so positioned 95 on the shaft 20 that when the movable clamp is moved to stretching position, said eccentrics will be effective in holding the shiftable clamp against accidental movement and there will be no danger of the shiftable 100 clamp slipping back toward the immovable clamp, unless the lever 21 is operated. It is obvious that any means may be provided for holding the lever 21 rigid with respect to the frame after the movable clamp is shifted. 105

By reference to Fig. 1 it will be seen that I contemplate rotating the shifting devices, to wit, the eccentrics 19 at a plurality of

points along the frame and I may employ as many or as few of these eccentrics as are necessary to perform the work involved.

I will not specifically describe any particular form of clamp, because the specific form of clamp is not a part of the invention. I reserve the right to employ any form of clamp which will be suitable for the work to be performed.

10 1. I claim as my invention:

1. A warp frame having an immovable clamp; and a movable clamp; an oscillatory shaft and eccentrics on said shaft and movable upon the movement of the oscillatory shaft to impart movement to the movable clamp.

2. A warp frame having an immovable clamp; a movable clamp having slotted connections with said frame; a rock shaft; and means on said shaft within the slots of said connections for imparting movement to the movable clamp upon a movement of said shaft.

3. The combination of means for supporting an immovable clamp and a movable clamp; the support for the movable clamp being provided with a slot; a projection carried by the movable clamp and extending within said slot; and means within said slot and engaging the projection to shift said movable clamp.

4. A frame comprising a plurality of yokes provided with slotted terminals; a movable clamp having projections extending within said slotted terminals; and means

within the slots for engaging the projections for imparting movement to the movable clamp.

5. In a warp frame, in combination, a frame; a clamp fixed to said frame; a clamp 40 slidably mounted on said frame; a rock shaft carried by said frame; and a plurality of eccentrics fixed on said shaft and operatively connected to said slidable clamp for sliding the latter.

6. In a warp frame, in combination, a plurality of yokes rigidly connected together in parallel relation; a clamp fixed to one arm of said yokes; a clamp slidably connected to the other arm of said yokes; a rock shaft mounted in said yokes; and connections between said shaft and said slidable clamp for moving the latter when the shaft is rocked.

7. In a warp frame, in combination, a plurality of yokes rigidly connected together in parallel relation; a clamp fixed to one arm of said yokes; a clamp having a slide dovetail connection with the ends of the other arms of said yokes, said ends being slotted; a rock shaft carried by the slotted ends of said yoke-arms; eccentrics on said shaft within the slots; and slotted members attached to said slidable clamp and extending into the slots in the yoke-arms and engaged by said eccentrics.
